CIRCUIT INTERRUPTER APPARATUS

Joseph Slepian, Pittsburgh, Pa., assignor to Westinghouse Electric & Manufacturing Company, East Pittsburgh, Pa., a corporation of Pennsylvania

Application September 15, 1939, Serial No. 295,098

8 Claims. (CL 200—150)

My invention relates to circuit interrupting systems, and has particular relation to apparatus in which the arc is extinguished in a liquid, such as oil, when a circuit breaker is opened.

5 In circuit interrupters constructed in accordance with the teachings of the prior art, the arc ignited between the contacts, when they are opened, is moved rapidly through the liquid. As a result of the motion vigorous turbulence is created and the ionization which tends to maintain the arc is suppressed. Circuit interrupters depending on turbulence for deionization have operated satisfactorily for voltages of moderate magnitude. I have found, however, that for relatively high potentials of the order of several hundred kilovolts, considerable time is required to completely extinguish the arc, and at times, the breaker fails entirely because the arc continues for an excessive interval. In a circuit breaker for 287 kilovolts, ten three-inch breaks were found to be necessary.

It is, accordingly, an object of my invention to provide an arc-extinguishing device for a circuit breaker designed to interrupt a relatively high potential.

Another object of my invention is to provide a device for quickly extinguishing the arc which is ignited when a circuit breaker designed to interrupt a high potential of the order of several hundred kilovolts is opened.

More specifically stated, it is an object of my invention to provide in a circuit breaker having a high voltage rating for an alternating current system, a contrivance by the operation of which the arc shall be completely extinguished within an interval of time corresponding to one cycle of alternating current at a frequency of the impressed voltage on the system in which the breaker is connected.

40 My invention arises from the realization that there is a limit to the voltage which can be handled in the prior art apparatus after arc extinction because the gases generated by the arc are not removed from the potential field. As the arc moves through the liquid in the prior art apparatus, it leaves behind it a series of bubbles. At current zero the volume of the arc enclosing bubble is greatly reduced compared to the bubble which would exist if there were no arc motion. 45 The interrupting ability of the breaker depends on the reduction in the section of the bubble which thus takes place. The bubbles contain gas which is of much lower dielectric strength than the oil and because they remain between the contacts of the breaker, an arc is reignited in the

bubbles with return of the high voltage after the original arc has been extinguished.

My invention contemplates the removal of the bubbles which the arc leaves behind it from the field between the electrodes. In accordance with 5 my invention, the arc is rotated in a closed curve, such as a circle, and is at the same time confined between insulating baffles which permit the liquid to circulate freely. The rotation is produced by a magnetic field which is of sufficient magnitude 10 to produce a high velocity. In general, I have found that for the interrupters with which I am primarily concerned, the field may have a magnitude in gauss equal to one-half the arc-current in amperes. In one case to which my invention is applicable the arc-current flow is of the order of 8000 amperes. The motion of the arc imparts a rotational velocity to the liquid and the ionized bubbles are removed from the region between the electrodes and projected into the 15 region between the baffles by the circulation of the liquid which results from the centrifugal force in the liquid.

The novel features that I consider characteristic of my invention are set forth with particularity in the appended claims. The invention itself, however, both as to its organization and its method of operation, together with additional objects and advantages thereof, will best be understood from the following description of a specific 20 embodiment when read in connection with the accompanying drawing, in which:

Figure 1 is a view partly in section, showing a circuit breaker in accordance with my invention;

Fig. 2 is an enlarged view in perspective showing the formation of bubbles between the contacts of a circuit breaker when the arc is moved; and

Fig. 3 is an enlarged view in perspective showing the removal of the bubbles formed between 40 the contacts in accordance with my invention.

The apparatus shown in Figure 1 comprises a tank 5 of the usual structure containing an insulating liquid, such as a suitable oil, for example. A pair of threaded terminal rods 7 extend through insulating bushings 9 which project into the tank through the top 11. Shields 13 of an insulating material such as porcelain cover the bushings 9 and are supported by discs 15 which are screwed on the rods 7 and abut against washers 17. 45

The fixed contacts 19 of the circuit interrupter are supported from brackets 21, each of which consists of a disc-shaped portion 23 having a central threaded boss 25 extending at an oblique angle to the disc. The terminal rods 7 are 50 55

screwed into the bosses 25 and the fixed contacts 19 are thus suspended from the rods. An assembly consisting of a cylindrical insulator 27 and a stack of annular insulating baffles 29 of substantially the same outer diameter as the disc 23 and the insulator 27 abuts the face of the disc opposite to the boss 25. The baffles 29 are held apart by spacers 31 and abut the lower side of the insulator 27. The insulator and baffle assembly is held together by insulating bolts 35 which extend through the baffles, the spacers and the insulator and engage threaded openings on the ring of the disc portion 23 of the bracket 21. The spacers 31 are of small diameter and have a thickness to provide sufficient space between the baffles 29 to permit the liquid to freely move therebetween. The insulators 27 have an annular recess extending upwardly from the lower side thereof to form a central projection 37 and an outer rim portion 33.

The fixed contacts 19 are of ring cross-section and are secured to the central projections 37 of the insulator 27. A coil 39 which provides a magnetic field for rotating the arc is disposed in the recess between the rim 33 and the central projection 37 of each of the insulators 27 and is supported on the baffle 29 which abuts the insulator. The upper terminal 41 of each coil 39 is connected to the lower face of the corresponding bracket 21 and the lower terminal 43 is connected to the corresponding fixed contact 19. The coils 39 are thus in circuit with the terminal rods 7 and the fixed contacts 19.

The movable contacts 45 are also of ring cross-section and are mounted near the ends of a conducting cross bar 47. A slideable lift rod 49 is secured at the center of the bar 47 and the rod is moved up and down to engage and disengage the contacts 19 and 45. The mechanism for moving the rod may be any device well known in the art, and as it does not concern the invention, it is not shown.

When the contacts 19 and 45 are closed, current flows in a path extending through one of the terminal rods 7, through the corresponding coil 39, the corresponding contacts 19 and 45, the cross bar 47, the contacts associated with the other terminal and the other coil 39 to the other terminal. No difficulty is involved from the fact that the coils 39 are in circuit with the contacts 19 and 45 as the coil impedance is small.

When the contacts are opened, arcs are ignited between each fixed contact 19 and the associated movable contact 45. Under the action of the magnetic field produced by the coils 39, the arc is moved rapidly around the erstwhile engaging surfaces of the contacts. As it moves, it leaves behind it a series of bubbles. The structure and formation of the bubbles can be seen from Fig. 2. When the arc is first ignited between the contacts the heat vaporizes the oil enclosing it and a bubble 51 enclosing the arc is formed. As the arc moves around the contacts 19 and 45 it leaves behind it a mass of smaller bubbles 52. As the current flow through the arc decreases, the volume of the arc-enclosing bubbles decreases until a thin column of gas, as represented by the line 53 in Fig. 2, remains. The original arc disappears in the region of this bubble 53. However, if the mass of small bubbles 52 remain between the electrodes, they provide a space of low dielectric strength in which the arc is reignited when the potential rises from the zero value.

In accordance with my invention, the reignition 75 is prevented by the removal of the bubbles. The

rotation of the arc produces substantial motion in the liquid and under the centrifugal force the liquid moves outwardly and carries with it the bubbles 52 as shown in Fig. 3. The bubbles are further broken up by the insulating baffles 29 and there is no ionized region in which the arc may be reignited.

Although I have shown and described certain specific embodiments of my invention, I am fully aware that many modifications thereof are possible. My invention, therefore, is not to be restricted except insofar as is necessitated by the prior art and by the spirit of the appended claims.

I claim as my invention:

1. A circuit interrupter comprising a liquid medium, cooperative contacts to be engaged and disengaged and having engaging surfaces permitting the point-to-point movement of an arc ignited between them immersed in said medium, means for restricting the arc to the region of said contacts but permitting the free circulation of said liquid, and means for moving an arc, after it has been ignited, over said engaging surfaces at a speed such that the force arising from the resultant motion of the medium in a direction transverse to the arc ejects the bubbles left by the arc as it moves from the vicinity of said contacts and said restricting means.

2. A circuit interrupter comprising a liquid medium, cooperative contacts to be engaged and disengaged and having engaging surfaces permitting the point-to-point movement of an arc ignited between them immersed in said medium, a plurality of insulating baffles disposed to restrict the arc to the region of said contacts but permitting the free circulation of said liquid, and means for moving an arc, after it has been ignited, over said engaging surfaces at a speed such that the force arising from the resultant motion of the medium in a direction transverse to the arc ejects the bubbles left by the arc as it moves from the vicinity of said contacts and into the region between said baffles.

3. A circuit interrupter comprising a liquid medium, cooperative contacts to be engaged and disengaged and having curvilinear engaging surfaces permitting the point-to-point movement of an arc ignited between them, means for restricting the arc to the region of said contacts, and means for moving an arc after it has been ignited, over said surfaces at a speed such that the centrifugal force arising from the resultant motion of said liquid in a direction transverse to said arc ejects the bubbles left by the arc as it moves from the vicinity of said contacts and beyond said restricting means.

4. A circuit interrupter comprising a liquid medium, cooperative contacts to be engaged and disengaged and having curvilinear engaging surfaces permitting the point-to-point movement of an arc ignited between them, a plurality of insulating baffles disposed to restrict the arc to the region of said contacts, and means for moving an arc after it has been ignited, over said surfaces at a speed such that the centrifugal force arising from the resultant motion of said liquid in a direction transverse to said arc ejects the bubbles left by the arc, as it moves, from the vicinity of said contacts and into the region between said baffles.

5. A circuit interrupter comprising a liquid medium, cooperative contacts to be engaged and disengaged and having engaging surfaces permitting the point-to-point movement of an arc

5 ignited between them immersed in said medium, means for restricting the flow to the region of said contacts, said restricting means being permeable to the fluid from the region of said arc, and means for moving an arc, after it has been ignited, over said engaging surfaces at a speed such that the force arising from the resultant motion of the medium in a direction transverse to the arc ejects the bubbles left by the arc as it moves from the vicinity of said contacts and said restricting means.

10 6. In a circuit interrupter, a quantity of arc extinguishing liquid, arc terminal members immersed in said liquid, said arc terminal members being spaced from each other at least during the circuit interrupting operation and being arranged to provide generally annular arc terminal paths thereon, means for establishing an arc between said arc terminal members, means for moving said arc laterally along said arc terminal paths at a speed such that liquid is caused to flow in a direction transverse to said arc, and means for restricting said arc to the region between said arc terminal members, said arc restricting means being pervious to the flow of liquid and arc gases to enable said moving liquid to sweep the arc gases from the region between said arc terminal members.

15 7. In a circuit interrupter, a quantity of arc extinguishing liquid, arc terminal members immersed in said liquid, said arc terminal members being spaced from each other at least during the circuit interrupting operation and being arranged to provide generally annular arc terminal paths thereon, means for establishing an arc

20 between said arc terminal members, baffle members disposed to confine the arc to the space between said arc terminal members, and means for moving the arc laterally along said arc terminal paths at a speed such that a quantity of said liquid is caused to be moved outwardly through said baffle members, said baffle members being so arranged to permit the free flow of liquid therebetween to enable said moving liquid to carry the arc gases from the space between said arc terminal members.

25 8. In a circuit interrupter, a quantity of arc extinguishing liquid, a pair of arc terminal members immersed in said liquid and being adapted to be separated from each other at least during the circuit interrupting operation, said arc terminal members having annular arc paths thereon between which an arc is adapted to play, means for establishing an arc between said arc terminal members, a plurality of insulating barrier plates of annular form disposed in spaced relation with respect to each other and about said arc terminal members so as to restrict the outward movement of said arc beyond said annular arc paths, and means for spinning said arc laterally around said annular arc paths at a rate sufficient to cause a radial flow of liquid away from the space between said arc terminal members and through the spaces between said barrier plates, said flow of liquid being sufficient to sweep the arc gases from the space between said arc terminal paths and discharge said gases through the spaces between said barrier plates.
